UNITED STATES PATENT OFFICE.

JOHN G. POWELL, OF PHILADELPHIA, PENNSYLVANIA.

IMPROVEMENT IN RUFFLING ATTACHMENTS FOR SEWING-MACHINES.

Specification forming part of Letters Patent No. 131,300, dated September 10, 1872.

To all whom it may concern:

Be it known that I, JOHN G. POWELL, of the city, and county of Philadelphia, in the State of Pennsylvania, have invented certain new and useful Improvements in Sewing-Machines, of which the following is a specification, reference being had to the accompanying drawing, which shows, in—

Figure 1, a view, in perspective, of a Howe sewing-machine with my improvements applied thereto; Figs. 2 and 3, views, in elevation, of those parts of said machine which embody my said improvements.

I wish it to be understood that my improvements may be applied to any sewing-machine now in use, the one shown in the drawing being simply selected for present convenience.

The object of my invention is to sew and gather or ruffle simultaneously; and my invention consists in an improved ruffling or gathering attachment, connected only with the presser-foot of the machine and operated by the needle-bar, as hereinafter more fully described.

I have shown in the drawing a stud projecting from the needle-bar, (see *f*, Fig. 1,) which, on the down-motion of said bar, depresses the plate-spring *E* and extends the ruffler-plate *C*. When the needle-bar rises the ruffler-plate is retracted and the ruffling-feed effected by the recoil of the spiral spring *G*. *B* is a guide-plate attached to the inner side of the presser-foot *A*, and in which the ruffler-plate traverses, as hereinafter more fully described. The ruffler-plate *C* is a strip of metal cut along its length so that the back part fits snugly in the guide *B*, while the front part of it rests against the under side of the presser-foot; and, to secure a proper pressure of the ruffler-plate against the presser-foot, the outer end of the ruffler-plate bears against a wedge-shaped piece, *b*. The front edge of the ruffler-plate is flush with the front edge of the presser-foot. On the inner front corner of the ruffler-plate is mounted a slotted stud-piece, *D*, having a set-screw, *d*, for a purpose to be presently described. To the heel of the presser-foot *A* one end of a plate-spring, *E*, is attached,

and the other end of the plate-spring bears against the stud-piece *D*. The plate-spring is thus arched so that its center is under the stud *f* on the needle-bar *F*. It will now be seen that by moving the stud-piece toward or from the heel of the presser-foot the flexure of the plate-spring will be greater or less, and the consequent travel of the ruffler-plate in the guide or the ruffler-feed increased or diminished, thus determining the closeness of the ruffling. The set-screw *d* serves to hold the stud-piece in the desired position. A spiral spring, *G*, is attached by one end to the instep of the presser-foot, and by the other end to that part of the ruffler-plate *C* which plays in the guide *B*.

The fabric to be ruffled is placed between the presser-foot and the ruffler-plate, and the operation of the machine is as follows: As the needle passes through the cloth the stud on the needle-bar depresses the plate-spring *E*, thereby extending the ruffler-plate, as shown in Fig. 3. Upon the rise of the needle and the release of the plate-spring, the spiral spring *G* retracts the ruffler-plate suddenly and more rapidly than the machine feeds the cloth, and thus produces the gather or ruffle.

It will be seen that by this construction of my improved presser-foot ruffler the entire device is only connected with, and is raised and lowered with, the presser-foot, and the machine can be used for plain work without detaching any of the parts, or for ruffling without any change other than placing the fabric upon the ruffler-plate.

What I claim as my invention, and desire to secure by Letters Patent, is—

1. The reciprocating ruffler-plate and its connecting-springs, arranged on the presser-foot, as described, and operated by the needle-bar.
2. The combination, with the above, of the adjusting device for governing the extent of movement of the ruffler-plate.

JOHN G. POWELL.

In presence of—

WM. B. DAYTON,
J. SNOWDEN BELL.
